AUGUST EUGENE ANDERSON, OF MONTCLAIR, NEW JERSEY.

CONTACT FOR SPARK-GAPS.

1,401,231.

Specification of Letters Patent. Patented Dec. 27, 1921.

Application filed July 9, 1921. Serial No. 483,510.

To all whom it may concern:

Be it known that I, AUGUST EUGENE ANDERSON, a citizen of the United States, and a resident of the town of Montclair, in the county of Essex and State of New Jersey, have invented certain new and useful Improvements in Contacts for Spark-Gaps; and I do hereby declare the following specification to be a full, clear, and exact description of my said invention, such as will enable others skilled in the art to which it appertains to make and use the same, reference being had to the accompanying drawings, and to reference characters marked thereon, which form a part thereof.

My invention relates generally to contacts for spark-gaps and particularly to ignition devices for explosive engines, in which the compressed charge is fired by an electric spark, and more particularly to an arrangement of the terminals of a spark-plug.

The objects of my invention are to provide a spark-gap for an explosive engine, or the like, whose terminals shall be kept clean automatically. Other minor objects will hereinafter be set forth.

My invention consists, broadly stated, in mounting a spark-plug, connected in the usual manner, in a magneto and distributer circuit, upon the cylinder of an explosion engine, but differing from the usual practice in this, that the spark-plug carries only one spark-terminal as a fixed electrode, the other spark-terminal being mounted upon the top of the piston-head as a traveling electrode, and in wiping contact with the bore of the piston-cylinder.

In the accompanying drawings which illustrate the preferred embodiment of my invention as applied to the piston and its cylinder of an explosive engine, Figure 1 is a sectional view in elevation of an engine cylinder and of the piston working therein, parts of both being broken away, and Fig. 2 is an enlarged perspective view of the two electrodes affording the spark-gap therebetween. Like numerals of reference indicate the like parts in these figures, in which 1 is an engine cylinder, shown as having the water-cooling jacket 2 thereabout. 3 is a piston-head working in said cylinder having the beveled top 4. 5 is a spark-plug screwed into the crown 6 of said cylinder and extending therethrough into the combustion or explosion chamber 7. 8 is a porcelain sleeve serving to insulate the conductor 9 which

terminates below in the electrode 10, and forming with the nut 11 a threaded binding-post at the upper end adapted to be connected to a distributor and through it to a source of current such as a magneto, neither of which parts are necessary to be shown. The electrode 10 is bent at right angles to the conductor and extends radially inward until its tip is substantially in alignment with the bore of the cylinder. 12 is a rectangular bracket, attached by the screws 13 to the top of the piston-head and in electrically conductive relation therewith, extending vertically upward to form a second electrode 14, whose path, as the piston reciprocates, brings it into sparking-relation to the electrode 10, the gap therebetween approximating between $\frac{1}{32}$ and $\frac{1}{64}$ of an inch. The electrode 14 is so mounted upon the piston as to engage frictionally at each piston-stroke in wiping contact with the inner surface of the cylinder. By such contact, the traveling electrode 14 is kept clean and bright and the establishment of the spark between it and the fixed electrode 10 is thereby insured.

As will be obvious, the electric current may be supplied from any suitable source and applied through any of the usual forms of distributors to my type of spark-gap, which may be used to ignite a charge of explosive fuel compressed in a cylinder by a piston in any kind of engine in which a spark-plug is now used, as a substitute therefore, by so attaching an angle-bracket to the piston-head that the side of one of its arms will be wiped clean at each piston stroke and caused to approach the fixed electrode, the circuit from the magneto being grounded or completed through the engine frame. I have found from extended use through a series of test conditions that the traveling electrode keeps free from fouling and presumably because of this fact that the fixed electrode retains its clean condition. In consequence of the non-fouling of these electrodes with carbon deposit and the like, the running of an engine equipped therewith is markedly improved. In comparative tests between the same automobile engine when equipped with spark-plugs of a standard form and when equipped with the same plugs changed over to produce my novel spark-gap, the engine picked up more quickly, the car climbed grades in high gear which it could not ascend otherwise except by shifting out of

high and the engine required twenty-five per cent. less gasoline fuel for the same distance, although while equipped with the normal spark-plugs they were clean at the start and 5 cleaned every hour during the test.

It will be understood that the traveling electrode in my system may be mounted in any suitable manner upon the piston-head, as by mechanical means, as illustrated, or 10 otherwise fastened thereto, or may be formed integrally therewith, and that the fixed electrode may be of any suitable character, so long as the invention is realized and practicable therewith.

15 Having thus described my invention, I claim as new:

1. In an explosion engine, a stationary electrode and a traveling electrode adapted to move into sparking relation with said 20 stationary electrode, and means adapted automatically to wipe said traveling electrode when out of sparking-relation to said stationary electrode.

2. In an explosion engine, a cylinder and a 25 piston therein, a stationary electrode in said

cylinder and a traveling electrode upon said piston, the traveling electrode being adapted to contact with said cylinder in wiping engagement therewith.

3. In an explosion engine, a cylinder and 30 a piston therein, an electrode mounted in the wall of said cylinder and a second electrode mounted upon the said piston and in wiping contact with said cylinder.

4. In an explosion engine, a cylinder and 35 a piston therein, an electrode mounted in the crown of said cylinder and a second electrode mounted in the head of said piston, and means adapted automatically to wipe said second electrode.

5. In an explosion engine, a cylinder and 40 a piston therein, an electrode mounted in the wall of said cylinder and a second electrode mounted upon the head of said piston and adapted to be moved thereby into sparking 45 relation to the other electrode and frictionally to engage the bore of said cylinder during a part of the piston's stroke.

AUGUST EUGENE ANDERSON.
